UNITED STATES PATENT OFFICE.

HENRY O. ROOP, OF CARROLLTON, GEORGIA.

PLOW.

SPECIFICATION forming part of Letters Patent No. 288,666, dated November 20, 1883.

Application filed June 23, 1883. (No model.)

To all whom it may concern:

Be it known that I, HENRY O. ROOP, a citizen of the United States, residing at Carrollton, in the county of Carroll and State of Georgia, have invented a new and useful Plow, of which the following is a specification, reference being had to the accompanying drawings.

This invention relates to certain new and useful improvements in plows; and it has for its object to provide a detachable point and detachable and adjustable wings, whereby the plow may be made capable of performing the work of a land-turner or a scraper, or both these functions at the same time; and with these ends in view my invention consists, essentially, of a plow-point and two independent wings, adapted to be secured together and to the plow-standard by means of a single bolt; and it has for its further object to provide a combined land-turner and plow-fender, the same consisting of a device formed into a wing at one end and into a vertical fender at the other, adapted to be secured to the point and standard by a single bolt, the peculiarities of which will more fully hereinafter appear.

In the accompanying drawings, forming a part of this specification, and on which like letters of reference indicate corresponding parts, Figure 1 represents a perspective view of my improved plow, showing the point and the independent wings attached thereto; Fig. 2, a detached plan view of the plow-point and the wings, showing the construction by which they are adapted to be adjusted; and Fig. 3, a detached perspective view of the combined wing and fender and the plow-point.

The letter A indicates a plow-beam provided with the usual handles and a standard, B, constructed, preferably, of a single piece of wrought-iron, having its ends secured to the beam, whereby a slot, C, is formed. The beam and standard are braced by a bar, D, secured, respectively, to the beam and to the standard. These parts, however, do not form any material part of my invention, and may be of any approved construction.

The letter E refers to the plow-point, the

same being constructed, preferably, of cast metal, having its point chilled or made of steel, and provided near its upper end with a rectangular opening, F; and the letter G refers to a metal bar secured to the plow-standard, near its upper end, by means of a bolt and strap, H, the lower end of which has an opening corresponding to that in the plow-point; and the under side of its lower end is provided with a shoulder, P, against which the upper end of the point abuts, whereby the point is prevented from sliding upwardly upon the standard.

The letter I indicates two wings, constructed each of metal, and preferably of the form indicated in the drawings, the said wings constituting the mold-board of the plow, their forward edges being straight, or approximately so, and their rear edges curved to any proper degree. Each of these wings, near its lower end, is provided with a rectangular aperture, J, having V-shaped notches K cut in each of its sides, agreeing in size with that in the plow-point. A bolt, L, having a square shank, is passed through these several apertures and between the side pieces of the standard, and provided with a nut, whereby the several parts are firmly bound together and held to the standard. When it is desired to adjust either or both of the wings, the nut is unscrewed, the bolt slipped out or partially out of the apertures, and the wings set in the desired position, the V-shaped notches in the apertures of which embrace the corners of the bolt-shank. When it is desired to form the land-turner on one side and the scraper on the other, only one of the wings is adjusted.

The letter M refers to the combined wing and fender, which, though it may be constructed of separate pieces, as are the two wings just described, may be constructed of a single piece, as in the present instance. The wing is substantially like those just described, and the fender is formed by bending up or casting the opposite portion of the stop at a right angle to the plane of the plow-point, whereby the fender is made to protect small plants. The intermediate portion, N, is provided with a transverse slot, O, by means of which the

wing and fender are secured to the point and plow-standard by the bolt L, whereby, also, it may be rigidly adjusted.

Having thus fully described my invention, 5 what I claim as new, and desire to secure by Letters Patent, is—

The combination of the standard B, having slot C, the plate G, having shoulder P, the bolt and strap H, the wings I I, having rectangular apertures J, provided with V-shaped notches K, the plow-point E, having rectangular opening F, and the square-shanked bolt L, all arranged and operating substantially as set forth.

In testimony that I claim the foregoing as 15 my own I have hereto affixed my signature in presence of two witnesses.

HENRY ONAN ROOP.
